(57) **CLAIM**

The ornamental design for a gripping head for pop-up sprinkler, as shown and described.

DESCRIPTION

FIG. 1 is a perspective view of a gripping head for pop-up sprinkler, showing my new design.

FIG. 2 is a top view thereof.

FIG. 3 is a bottom view thereof; and,

FIG. 4 is a side view thereof, whether viewed from the front, rear, left or right side.

The broken line showing of a gripping head is included for the purpose of illustrating portions of the article and forms no part of the claimed design.
